D10-1.

OR D 7,767 EX

UNITED STATES PATENT OFFICE.

FLORENCE KROEGER, OF HOBOKEN, NEW JERSEY.

DESIGN FOR CLOCK-CASES.

Specification forming part of Design No. 7,767, dated September 22, 1874; application filed August 15, 1874.
[Term of Patent 3½ years.]

CASE B.

To all whom it may concern:

Be it known that I, FLORENCE KROEGER, of Hoboken, in the county of Hudson and State of New Jersey, have invented a new and original Design for a Clock, of which the following is a specification:

The engraving represents a face view of my new design for a clock.

This invention relates to a new configuration of the case for a pendulum-clock, and to a new ornamentation of the same.

The opening through which the dial and pendulum are visible is in form of an arch, surrounded by a suitable molding, *a*, whose ends rest upon the base *b* of the case. This base is made of suitable design. The upper end of the clock-case is also arched, but eccentric to the arch over the dial, as shown, and is crowned by a shell, *d*, which rests in

two converging scrolls, *e e*, as shown. The ends of the crowning arch *i* terminate in rosettes *f f*, that rest on corbels *g g*. The truss part of each corbel is in form of a volute, which extends nearly half-way down to the base, and is almost met by an upwardly-projecting leaf, *h*, that grows out of the end of the base, as shown. The face of the case may be ornamented by suitable panels or scrolls.

I claim as my invention—

1. The design for the configuration of a clock, composed of the parts *b, h, g, i*, and *d*, as shown.

2. The design for the ornamentation of an arched clock by the parts *e e* and *f f*, as shown.

F. KROEGER.
